Primary Examiner — Clare E Heflin(74) *Attorney, Agent, or Firm* — James A. Gavney, Jr.; JAG Patent Services(57) **CLAIM**

We claim the ornamental design for a bottom glow linear light fixture, as shown and described.

DESCRIPTION

FIG. 1 is a perspective view of a bottom glow linear light fixture showing my new design;

FIG. 2 is a front or a back view of the bottom glow linear light fixture thereof;

FIG. 3 is a top view of the bottom glow linear light fixture thereof;

FIG. 4 is a bottom view of the bottom glow linear light fixture thereof; and,

FIG. 5 is a right side or a left side view of the bottom glow linear light fixture thereof.

The broken lines shown on the drawings depict environment and form no part of the claimed design.
